UNITED STATES PATENT OFFICE

NATHAN MYRE, OF TOLEDO, OHIO

AMUSEMENT DEVICE

Application filed February 27, 1930. Serial No. 431,915.

This invention relates to amusement devices, but more particularly to such device commonly known as the "African dip", which utilizes a platform on which a person is seated, and beneath is a receptacle of water; targets are so connected or associated with the platform that if the target is properly hit the platform is released and the person precipitated into the water.

10 An object of this invention is to improve previous constructions to render them more efficient in every way.

Another object is to produce a device of the above character in which the platform 15 is automatically returned to normal position after the weight has been discharged therefrom.

A further object is to produce a new and improved target construction, which is simple in arrangement, and reliable in operation.

Other objects and advantages will herein-after appear, and the invention is shown by way of illustration on the accompanying 25 drawings, in which—

Fig. 1 is a perspective view of the amusement device;

Fig. 2 is a vertical sectional elevation of the target;

30 Fig. 3 is a rear end view of the target with a portion of the rear wall broken away;

Fig. 4 is a vertical sectional elevation of the platform in associated parts; and

Fig. 5 is a transverse sectional elevation 35 on the line 5—5 of Fig. 4.

The illustrated embodiment of the invention comprises a standard 1, which supports a box 2, to one side of which is fulcrumed a platform 3. The platform 3 is fulcrumed 40 intermediate its ends as at 4, and one end portion of the platform projects beyond the adjacent side of the box 2 substantially as shown. Beneath the outer or projecting end of the platform 3 is a tub 5 adapted to 45 contain water, and is arranged in such position that upon release of the platform 3 a person seated on the projecting end thereof will be discharged or precipitated into the tub. This action will take place when a 50 successful contestant properly hits one of

the targets 6 with a ball or the like, the targets being so connected with the platform 3 that when hit the platform is released and over-balanced by the weight of the person seated thereon. Details of the construction 55 and arrangement follow.

Pivoted to the rear end portion of the platform 3 at 7 is a depending arm or rod 8, having a notched recess 9. Engageable with the notch 9 is an inverted U-shape catch 60 member 10, which is supported by bearing blocks 11^a on the floor of the box 2. An arm 11 extends from the catch 10, and a rod 12 connects the arm 11 to a bell crank lever 13 pivoted to a side wall of the box. 65 Through a pin and slot connection the bell crank lever 13 is connected by a vertically disposed shaft 14 with an electro-magnetic device 15. The arrangement is such that when the electro-magnetic device 15 is energized the catch 11 is actuated in a counter clockwise direction (Fig. 4) to release the rod 8 so that the weight of the person on the projecting end portion of the platform 3 is sufficient to cause tilting of the platform, 70 75 and cause the person to be discharged therefrom.

After a person has been precipitated from the platform the weight of the inner end portion is sufficient to return the parts to 80 normal position so that the platform is in substantially horizontal relation. Thereupon the catch 10 is returned into notch engaging position to retain the platform in the desired position until further operation of 85 the electro-magnetic device 15. The electro-magnetic device 15 is connected by leads 16 to the targets 6, which comprise a frame member having a central opening 17, the rear end of which is covered by the swing- 90 target member 18. The target member is pivoted adjacent its upper end at 19, and is normally held in substantially vertical position by a coil spring 20. One of the leads 16 connects to a stationary curved plate 95 member 21 carried by the casing, and over which a roller 22 is adapted to ride when the target is hit and caused to move in a clockwise direction (Fig. 2). The roller 22 is carried by a rod 23, which is in turn con- 100

nected to the other lead 16. It is evident that upon engagement of the roller 22 with the intake plate 21 the circuit is closed, energizing the electro-magnetic device 15, and 5 causing the operation heretofore described.

Access to the interior of the target mechanism is afforded by a door 24 hingedly connected to the rear of the target frame.

While it is to be understood that the above 10 illustration is of the preferred form of my invention, numerous changes may be made in details of construction, arrangement and operation without departing from the spirit of the invention, especially as defined in the 15 appended claims.

What I claim is new and desire to secure by Letters Patent is:

1. In an amusement device, a platform 20 fulcrumed intermediate its ends, and adapted to receive a weight at one end thereof, a member pivoted to and depending from the opposite end portion of said platform, said opposite end and said member being of greater weight than said weight receiving 25 end, a trip member engageable with said pivoted member adapted normally to prevent said platform from swinging when a weight is imposed on the end thereof remote from said pivoted member, and means for 30 releasing said trip member to permit swinging of said platform whereby upon discharge of the weight the platform returns to normal position due to the greater weight on the end away from said weight-receiving 35 end.

2. In an amusement device, a platform fulcrumed between its ends and adapted to accommodate a weight such as a person at one 40 end, a depending member pivoted to the opposite end of said platform, said member being notched, a release member engaging said notch for preventing swinging of said platform when a weight is imposed thereon, and electro-magnetic means for actuating said 45 release member to permit tilting of said platform, thereby to discharge the weight, said platform being unbalanced to return automatically to normal position.

3. In an amusement device, a platform 50 fulcrumed between its ends and adapted to accommodate a weight such as a person at one end, a depending member pivoted to the opposite end of said platform, said member being notched, a U-shaped release member 55 engaging said notch for preventing swinging of said platform when a weight is imposed thereon, and electro-magnetic means for actuating said release member to cause tilting of said platform, thereby to discharge 60 the weight, said platform being unbalanced to return automatically to normal position.

4. In an amusement device, a platform 65 fulcrumed between its ends and adapted to accommodate a weight such as a person at one end, a depending member pivoted to the

opposite end of said platform, said member being notched, a release member engaging said notch for preventing swinging of said platform when a weight is imposed thereon, electro-magnetic means for actuating said 70 release member to cause tilting of said platform, thereby to discharge the weight, said platform being unbalanced to return automatically to normal position, a swingable target, and an electrical connection between said target and said electro-magnetic means, said connection including a curved contact plate and a member carried by said target and engageable with said plate.

5. In an amusement device, a swingable 80 platform adapted to receive a weight at one end, a depending member at the opposite end, a catch normally holding said depending member to prevent tilting and discharge of the weight, an electrical device for releasing said catch, said device including a swingable target having a contact member and a stationary curved plate normally away from said contact member whereby swinging of said target moves said member to said plate, 85 thereby to cause release of said platform, said platform being constructed and arranged automatically to return to normal position after discharge of the weight.

In testimony whereof I have hereunto 90 signed my name to this specification.

NATHAN MYRE.
